TRANSPARENCY VIEWER OR SIMILAR ARTICLE

Edgar I. Fuller, Roy, Wash.

Application July 11, 1956, Serial No. 42,208

Term of patent 14 years

(Cl. D61—1)

FIG. 1

Figure 1 is a perspective view looking toward the front and right hand side of a transparency viewer or similar article, showing my new design, and

The side not shown has substantially the same appearance as the side shown, and the back is conventional. Portions of the drawing figures are diagonally lined to indicate transparency.

I claim:

The ornamental design for a transparency viewer or similar article, substantially as shown and described.
